Hays.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,335,366.

Specification of Letters Patent. Patented Mar. 30, 1920.

Application filed January 31, 1919. Serial No. 274,313.

To all whom it may concern:

Be it known that I, FRED S. CARR, a citizen of the United States, and a resident of Newton, in the county of Middlesex, 5 Commonwealth of Massachusetts, (whose post-office address is care of Carr Fastener Company, Cambridge, Massachusetts,) have invented an Improvement in Fasteners, of which the following description, in connection with the accompanying drawings, is a specification, like characters on the drawings representing like parts.

This invention pertains to separable fasteners, and more particularly, though not 15 exclusively, to "one-way or three-side lock" fasteners including a stud and socket separable by relative tipping movement in one direction only.

Referring to the drawings:

20 Figure 1 is a front elevation of a preferred form of my invention;

Fig. 2 is a vertical section thereof on the line 2—2 of Fig. 1; and

25 Fig. 3 is a transverse section in the plane of Fig. 1 taken on the line 3—3 of Fig. 2.

In the preferred form of my invention selected for illustrative purposes I have shown a stud including a head 4, a shank 5, and a neck portion 6, and providing between 30 the head and the neck relatively abrupt shoulders 7. I have also shown a socket including the casing 8 containing jaws 9, 10 connected by spring portions 11—11. The socket also preferably includes a plate 35 12 having an aperture therein through which the stud can be entered. The jaws 9, 10 provide between them an aperture 13 adapted to engage and hold the stud by engagement behind the shoulder portion 40 thereof. As previously stated, the shoulders 7 are preferably relatively abrupt, that is, so abrupt that the stud can not be withdrawn from the socket rectilinearly by the application of any usual or desirable amount 45 of force. To permit ready separation of stud and socket, I bevel the jaws 9, 10 at one end, preferably as shown adjacent the terminal portions thereof, these bevels being numbered 14 and 15. When the socket is 50 tipped relative to the stud, or vice versa, in the direction of the arrows in Fig. 2, the abrupt shoulders of the stud will come in contact with the inclined surfaces 14, 15, thereby forcing the jaws 9, 10 apart and 55 permitting separation of stud and socket.

The stud may be entered in the socket by a direct or rectilinear movement because the rounded head of the stud will wedge apart the jaws 9, 10.

The preferred form of combined jaws and 60 spring shown in the drawings is preferably stamped from sheet metal and to preserve a predetermined relation between the socket and spring so that the direction of tipping movement can always be ascertained, I have 65 made the spring of irregular cross-section to fit the socket, thereby to prevent rotation or substantial movement of the spring and jaw portions relative to the socket. To maintain the aperture 13 between the jaws 70 9, 10 in line with the stud-receiving aperture in the back of the socket while leaving free play or freedom of movement to the spring portions 11—11, I have provided a projection in the casing 16 of the socket 75 adapted to centrally engage the spring and jaw elements, the projection being entered in indentation 17 therein. Thus when the socket is separated from the stud the aperture 13 will always be centered, and at the 80 same time the springing apart of the jaws and movement of the spring portions 11—11 toward the side of the casing will not be interfered with.

While I have shown and described a preferred form of one embodiment of my invention, it will be understood that changes involving omission, substitution, alteration and reversal of parts, and even changes in the mode of operation, may be made without departing from the scope of my invention, which is best defined in the following 85 claims.

Claims:

1. A stud and socket fastener comprising, 95 in combination, a stud having a head and a neck providing a relatively abrupt shoulder therebetween, and a socket therefor including a casing having a stud-receiving aperture and carrying two resiliently supported 100 jaw portions one at each side of the center of the aperture, said jaw portions being beveled at one end, whereby relative tipping of said stud and socket in a direction to bring said shoulder against the beveled end 105 of said jaw portions may separate said jaws to permit separation of stud and socket, while separation of said stud and socket by tipping movement in all other directions is prevented. 110

2. A "one-way" or "three-side lock" fastener comprising, in combination, a stud having a head and a neck providing therebetween a relatively abrupt shoulder, and a socket including a casing and two jaws connected by a flat sheet metal spring portion spaced from the casing throughout substantially its entire periphery, said jaws providing a stud-receiving aperture between them, and centering means for locating the jaws and the aperture relative to the casing while maintaining free movement of said spring portion.

3. A "one-way" or "three-side lock" fastener, comprising, in combination, a stud 15 having a head and a neck providing therebetween a relatively abrupt shoulder, and a socket including a casing and a resilient sheet metal jaw-carrying part contained therein and spaced from the casing throughout substantially its entire periphery, said 20 jaw-carrying part being held against rotation relative to said casing.

In testimony whereof, I have signed my name to this specification.

FRED S. CARR.
